UNITED STATES PATENT OFFICE.

MILTON N. GRANT, OF COLUMBUS, AND CARLTON J. GRANT AND ALEX H. GRANT,
OF GROVEPORT, OHIO.

ATTACHMENT FOR BRICK-MACHINES.

No. 893,796.

Specification of Letters Patent.

Patented July 21, 1908.

Application filed February 13, 1908. Serial No. 415,676.

To all whom it may concern:

Be it known that we, MILTON N. GRANT, a citizen of the United States, residing at Columbus, and CARLTON J. GRANT and ALEX H. GRANT, citizens of the United States, residing at Groveport, in the county of Franklin and State of Ohio, have invented certain new and useful Improvements in Attachments for Brick-Machines, of which the following is a specification.

Our invention relates to the improvement of brick machines and the objects of our invention are to provide in connection with a brick machine of the usual construction, improved means whereby the surfaces of a clay body ejected from the die of a brick machine may be roughened or corrugated; to so construct our improved corrugating device as to admit of the shaping of the clay body for the production of brick of different outlines and at the same time roughen or corrugate the exposed faces of the brick. These objects we accomplish in the manner illustrated in the accompanying drawing, in which:

Figure 1 is a perspective view of the delivery end of a brick making machine, showing our improved corrugating and shaping device in use thereon, Fig. 2 is a view in perspective of the corrugating and shaping device shown in Fig. 1, Fig. 3 is a longitudinal section of a portion of the clay body which is discharged from the brick machine showing our improved corrugating and shaping device in section therein, Fig. 4 is a view in elevation of a modified form of corrugating and cutting device, Fig. 5 is a view in perspective of a brick shaped and corrugated by the device shown in Fig. 2, Fig. 6 is a similar view of a different form of brick such as that which may be produced by the employment of the construction shown in Fig. 4, and, Fig. 7 is a view similar to that shown in Fig. 3 showing a modification in the manner of forming the shaping and corrugating bar.

Similar numerals refer to similar parts throughout the several views.

1 represents the discharging head of a known form of brick making machine and 2 the oblong die which is connected with the head and through which a body of clay such as is indicated at 3 is forced from the brick making machine in the usual manner on to a

cutting table, where said clay body is by wires or other suitable cutting devices, separated into bricks.

55

4 represents one form of our attachment which consists of a bar which is secured to the framework 1^a of the brick machine in such manner that said bar passes in front of the upper portion of the mouth of the die. In constructing the bar, one of the longer edges thereof which is nearest the die, is beveled or sharpened as indicated at 4^a, while on the underside of the bar is provided a longitudinal bead or projection 5 which as indicated in Fig. 3, may be in the nature of a rod suitably secured to the bar 4 or as indicated in Fig. 7 of the drawing, may be in the nature of a short downwardly projecting flange 5^a.

70

As the oblong body of clay is forced from the mouth of the die, the upper portion of the clay body comes into contact with the beveled edge of the bar 4, resulting in stripping a comparatively thin layer of clay from said body, such as is indicated at 6 in Figs. 3 and

7. As a further result of forcing the clay outward and its contact with the projection 5 or 5^a of the member 4, a portion of the clay forming the new surface of the body is alternately compressed in front of said projection and then forced beneath the latter and permitted to rise in rear thereof, this successive operation resulting in the production of transverse corrugations or depressions and intervening ridges on the surface of the clay body. When said clay body is cut into bricks, it is obvious that the surface thereof which has been acted upon, as described, by said projection 5, will present a roughened or substantially corrugated appearance.

In case it is desired to roughen or corrugate not only the upper surface of the brick, but one side thereof at right angles with said surface, it is obvious that the bar 4 may be provided with a right angle bend which is followed by the projection 5 and that such downwardly bent portion will serve to similarly shave the surface from the side of the clay body and roughen said surface.

100

In Fig. 4 of the drawing, we have shown a form of bar which includes a downwardly bent end portion for operation on the side of the brick, said downwardly bent portion

being shown concaved at 4° and said concaved portion having a vertical termination 4°. By the employment of a bar of this kind, it will be understood that the clay body 3, 5 will not only be formed with a concaved corner portion as shown in Fig. 1, but that said corner portion as well as the remainder of the side of the clay body will be roughened or corrugated to correspond with the upper 10 surface thereof.

In Fig. 4 of the drawing, we have shown a slightly modified form of cutting and corrugating bar, in which the connection between the downturned side portion and the upper 15 horizontal portion of the bar is rounded. A brick or clay body produced by the use of this form of bar, will result in the production of a brick such as that shown in Fig. 6 of the drawing.

20 While we have shown herein but two forms of shaping and corrugating bars, it will be understood that bars of a similar character having different outlines for the production of

brick of varying outline, may be used without departing from the spirit of our invention. 25

What we claim, is:

1. An attachment for the discharge end of a brick machine comprising a bar having one of its edges inclined and its underside provided with a projection extending lengthwise of the bar. 30

2. The combination with a brick machine and its discharging die, of a bar secured in front of said discharging die, said bar being shaped to conform to the shape of the brick to 35 be produced and having its underside formed with a longitudinal downwardly projecting bead.

In testimony whereof we affix our signatures in presence of two witnesses.

MILTON N. GRANT.
CARLTON J. GRANT.
ALEX H. GRANT.
